COAT HANGER

Robert W. Schier, Northfield, Ill., assignor to Krueger Metal Products, Inc., Green Bay, Wis., a corporation of Wisconsin

Filed Dec. 23, 1968, Ser. No. 15,078

Term of patent 14 years

Int. Cl. D6—07

U.S. Cl. D80—8

FIG. 1 is a front elevational view of a coat hanger embodying my new design;

FIG. 2 is a top plan view thereof;

FIG. 3 is an elevational view taken from one side thereof;

FIG. 4 is an elevational view taken from the side opposite that shown in FIG. 3;

FIG. 5 is a cross sectional view taken on line 5—5 of FIG. 1; and

FIG. 6 is a front elevational view of a modified form of the coat hanger shown in FIG. 1.

In both embodiments, the bottom is plain. The embodiment of FIG. 6 has the same appearance in plan, side elevation, and cross section as the embodiment in FIG. 1.

I claim:

The ornamental design for a coat hanger, as shown and described.
